COMBINATION SOUND RECEIVER, AMPLIFIER,
AND SPEAKER SYSTEM

W. Brent Hardy, 55 W. Louise Ave.,
Salt Lake City, Utah 84115

Filed Dec. 22, 1967, Ser. No. 9,895

Term of patent 3½ years

Int. Cl. D14—03

U.S. Cl. D26—14

FIG 1

FIG 2

FIG 3

FIG 4

FIG. 1 is an end elevation view of a combination sound receiver, amplifier and speaker system, with the case closed, showing my new design;

FIG. 2, a front elevation view;

FIG. 3, a rear elevation view; and

FIG. 4, a front perspective view, with the case opened.

I claim:

The ornamental design for a combination sound receiver, amplifier, and speaker system, substantially as shown and described.
